UNITED STATES PATENT OFFICE.

WYLIE GEMMEL WILSON, OF ELIZABETH, NEW JERSEY, ASSIGNOR TO EVERLASTING VALVE COMPANY, OF JERSEY CITY, NEW JERSEY, A CORPORATION OF NEW JERSEY.

AUTOMATIC SHUT-OFF DEVICE FOR GAS IN CASE OF FIRE.

Application filed April 3, 1925. Serial No. 20,454.

This invention relates to an automatic shut-off device for gas in case of fire.

The object of the invention is to produce a simple and durable device for installation in gas conduits whereby, in case of fire, flow of gas in the conduit will be automatically prevented. This invention is applicable to gas mains entrant into buildings; and to gas pipes within buildings for gas illuminating and power purposes and for gas ranges, heaters and other purposes. By automatically sealing a gas conduit in case of fire, more or less serious gas explosions are prevented and fire risks reduced.

In the accompanying drawing forming a part hereof and illustrating two different forms of my invention:

Fig. 1 is a vertical, central, sectional view of one form of my new automatic gas shut-off device shown as a union between gas pipe sections.

Fig. 2 is a vertical, central, sectional view of another form of said device coupling gas pipe sections.

Fig. 3 is a horizontal section at line 3—3 of Fig. 1.

Referring to the illustrated forms of the invention and first to that form shown in Figs. 1 and 3, my new device consists of a chambered union having a flat top wall, 2, a-linedly opposed, spaced apart neck conduits 3 and a downwardly extending bottom 4 which forms a pocket below the level of the necks 3. Each neck 3 is in threaded connection through a connecting sleeve 5 with a gas pipe section 6. The upper wall of the device is shown in Fig. 1 provided with a plurality of vertical, threaded openings 7. From the top and side walls of the union a transverse web 8 extends downwardly below the level of the necks 3 and part way to the bottom of the pocket formed by the downward extension of the bottom wall 4.

Normally the gas-way is through one conduit neck 3 towards a side wall of the web 8 and downwardly past the under edge of the web and thence upwardly to the other side of the web and out through the other gas conduit neck 3.

Into each threaded opening at 7 there is threaded a vertical fusible metal holder 9 in the form of an inverted cup and provided

at its bottom opening or mouth with inwardly projecting lugs 10 which serve to 55 protect the packing of fusible metal 8 in each of the holders.

The fusible metal is preferably in shredded form and packed solidly in the holders wherein it will remain in the absence of heat 60 sufficient to melt it for a long period, practically during the life of the device. Each load of the approximately solid, fusible metal 8 is thus held with its under end exposed to and spaced apart from the gas-way and chambered portion of the device, the under open ends of the holders being elevated relatively to the interior walls of the gas necks 70 sufficiently to permit unobstructed flow of gas from one pipe section to another through the union so long as the fusible metal remains unmelted.

In case of fire sufficient to heat the holder 7 and the masses of fusible metal 8 in the holders to a temperature sufficient to melt 75 the fusible metal, it flows downwardly when melted into the pocket formed by the downwardly extending bottom wall 4 and submerges the under end portion of the transverse web 8 in melted, fusible metal 8a. 80 Thus, the gas-way through the device is automatically sealed or dammed and flow of gas from one pipe section to another through the device or union is absolutely prevented. The fused metal will naturally solidify on 85 cooling and usually after a fire the device will not be removed until after the metal has cooled and solidified.

In addition to the above stated advantage of automatically sealing the gas-way 90 of the device against flow of gas during a fire, another important advantage is that the device when removed may be returned to a manufacturer to be freed of the seal-forming metal 8a and for reloading of the fusible metal holders 7.

While a plurality of holders 7 is indicated in Fig. 1, only one is essential together with its charge 8 of fusible metal. However, I show in Fig. 2 another form of the device in 100 which there is only one holder 7 and one charge 8 of fusible metal. The form of the device or coupling shown in Fig. 2 is identical in principle with that illustrated in Figs. 1 and 3, but is differently constructed. 105 It comprises a pair of chambered heads 4a

and 4^b, each having a gas conduit neck at its upper portion in threaded connection at 5^a with a gas pipe section *a*, the under ends of the two heads 4^a and 4^b are each in threaded connection with the upper end of a downwardly extending U-shaped pipe the bottom bent wall 4 of which forms a pocket for reception of an initially melted fusible metal seal or dam 8^a. The upwardly extending 10 inward walls 6^a of this bent section, at their bottom bend project downwardly part way to the bottom of the pocket formed by the under bent wall 4 of the upstanding U-shaped member of the union.

15 The holder 7 is shown severally provided with a detachable sleeve 9 of heat resisting and electric insulating material. Each sleeve is wound with the electric resistance coil 10, one terminal of which is indicated 20 by 11 and the other by 12. If a suitable electric current is passed through a resistance coil 10, the temperature of the sleeve and of the holder which is preferably of brass may be raised sufficiently to melt the 25 fusible metal 8 and thereby permit the automatic sealing of the gas-way from any desired distance or place.

What I claim is:

1. As a new article of manufacture, a gas 30 conduit member formed with a gas-way and a removable chambered holder closed at its upper end and having an open, under end in jointed connection with walls of an opening in the upper portion of the conduit member, said holder containing a mass of fusible metal exposed to and spaced apart from and above the gas-way; the gas-way being formed to receive the fusible metal when melted and thereby seal the gas-way 35 against flow of gas through the gas-way.

2. As a new article of manufacture, a gas conduit member formed with a gas-way and a removable chambered holder containing a 40

mass of fusible metal exposed to and spaced apart from and above the gas-way; the gas-way being formed to receive the fusible metal when melted and thereby seal the gas-way against flow of gas through the gas-way; the under end of the holder being open and the holder being provided at its under end portion with inwardly projecting means for retaining within it the fusible metal until melted. 45

3. The combination with a gas conduit member formed with a gas-way and a chambered holder containing a mass of fusible metal exposed to and spaced apart from and above the gas-way; the gas-way being formed to receive the fusible metal when melted and thereby seal the gas-way against flow of gas through the gas-way; of a heat resisting electric resistance coil support and said coil for raising, at the will of an operator the temperature of said coil to a degree sufficient to melt the fusible metal, the coil support being mounted on said holder and the coil surrounding the support and the support surrounding the holder. 50

4. The combination with a gas conduit member formed with a gas-way and a chambered holder containing a mass of fusible metal exposed to and spaced apart from and above the gas-way; the gas-way being formed to receive the fusible metal when melted and thereby seal the gas-way against flow of gas through the gas-way; a heat resisting electric resistance coil support and said coil for raising, at the will of an operator, the temperature of said coil to a degree sufficient to melt the fusible metal, the coil support being mounted on said holder and the coil surrounding the support and the support surrounding the holder. 55

Signed at Jersey City, State of New Jersey, this 25th day of March A. D. 1925.

WYLIE GEMMEL WILSON.
